(57) **CLAIM**

The ornamental design for ornamentation on a headwear piece, as shown and described.

DESCRIPTION

FIG. 1 is a front, top and side perspective view of a first embodiment of my design for ornamentation on a headwear piece, according to the present invention;

FIG. 2 is a reduced front elevation view thereof;

FIG. 3 is reduced top plan view thereof;

FIG. 4 is a reduced side elevation view thereof from the same side as in FIG. 1;

FIG. 5 is a perspective view of a second embodiment of my design for ornamentation on a headwear piece, according to the present invention;

FIG. 6 is a reduced front elevation view of my design in FIG. 5;

FIG. 7 is a reduced top plan view of my design in FIG. 5; and,

FIG. 8 is a reduced side elevation view of my design in FIG. 5 from the same side as in FIG. 5;

The portions of the headwear piece shown in dotted lines do not constitute a part of the claimed design.
